UNITED STATES PATENT OFFICE

2,503,737

WALL TOOL CHEST

Charles E. Hodgkins, Allston, Mass., assignor to
Lawrie L. Witter, Boston, Mass.

Application December 7, 1945, Serial No. 633,288

1 Claim. (Cl. 312—113)

1

This invention relates to a novel tool chest for conveniently supporting tools on a wall and housing the tools against removal or loss. A workman likes to have his tools within easy reach when working at the bench and he also likes assurance that his tools will not become lost or stolen. The primary object of my invention resides in the production of a novel wall tool chest that will serve both such functions.

My invention contemplates a tool supporting shelf adapted to be secured to the wall within easy reach of the operator and provided with means for receiving and supporting the tools. Also cooperating with the shelf is a housing that can be applied to the shelf and enclose the tools against loss. The housing can be locked in enclosing position on the shelf or can be completely removed to allow free access to the tools. Preferably the chest is made from sheet metal and is provided with interengaging guideways for receiving and supporting the housing on the shelf. The production of a new and improved wall tool chest of this nature comprises a further object of the invention.

These and other features of the invention will be best understood and appreciated from the following description of a preferred embodiment thereof selected for purposes of illustration and shown in the accompanying drawing in which:

Fig. 1 is a front elevation of my improved tool chest,

Fig. 2 is a sectional view taken on line 2—2 of Fig. 1, and

Fig. 3 is a fragmentary sectional plan taken on line 3—3 of Fig. 2.

In the drawing 10 indicates a tool supporting shelf preferably in the form of a sheet metal stamping. The shelf comprises a horizontal forwardly extending portion 12 provided with tool receiving holes 14 therethrough and an integral upwardly extending flange or bracket portion 16 at the rear for engaging against a wall 18. The portion 16 is provided with screw-receiving holes therethrough for screws 20 which secure the shelf to the wall. The holes 14 are of varied sizes and configuration to accommodate different tools permitting the handles of the tools 15 to extend downwardly through the holes as illustrated. The shelf will ordinarily be mounted on a wall adjacent to the work bench whereby to support the tools within easy reach of the workman. It will also be noted that the shelf is entirely open and permits free access to the tools.

My invention also contemplates a housing 22 for cooperating with the shelf and protecting the

tools against loss and exposure when they are not being used. The housing illustrated comprises a sheet metal unit having a front wall 24, a top wall 26 and end walls 28, all in one piece integral or otherwise. The ends 30 of the shelf 12 are bent upwardly and inwardly to form guideways for receiving outwardly extending flanges 32 on and extending along the bottom edges of the end walls 28, whereby the housing can be slid forwardly on and in interlocking engagement with the shelf 12. The depth of the housing corresponds with the width of the shelf so that the open rear side of the housing is disposed against the wall 18 when the housing is slid to its rear-most position. In Fig. 2 the housing is illustrated in an intermediate position. A lock 34 mounted on the housing, as by a plate 36 welded thereto, is provided with a bolt 38 for engaging in a slot 40 in the shelf, the lock being operated by a removable key 42. The lock provides means for securing the housing against unauthorized removal.

It will now be apparent that my invention provides a wall supported tool chest having a removable housing adapted to protect tools against loss and also providing an open tool supporting shelf convenient to the work bench when the housing is removed. The holes 14 through the shelf 12 permit the supporting of long handled tools in the chest and requires only sufficient housing capacity to care for the heads of the tools. Furthermore the downwardly extending handles permit the workman to see at a glance what tools are in the chest even when the housing is in place. It will also be noted that the housing not only prevents removal and loss of the tools but also prevents removal of the housing by preventing removal of the screws 20 that support the housing on the wall.

Having thus disclosed my invention what I claim as new and desire to secure by Letters Patent is:

A wall tool chest comprising a relatively long sheet metal shelf with an upturned flange at one of its long edges, the flange being perforated to receive screws for securing the shelf in horizontal position to a wall and the shelf having holes therethrough for the passage of the handles of tools supported on the shelf, said holes being of a size to permit downward passage of the handles therethrough but too small to permit passage of the relatively larger heads on the handles, a sheet metal housing having top, front and end walls, the top wall being of an area commensurate with the shelf, means providing interengaging guide-

ways on the ends of the shelf and housing for permitting forward-rearward sliding engagement of the housing into interlocking contact with the shelf and with the housing disposed above the shelf, the guideways permitting forward-rearward movement of the housing toward and from said wall into a position disposed over and covering the shelf and removal of the housing from the shelf, and means for locking the housing in said position, the shelf being adapted to support 10 said tools with the heads thereof resting on the shelf at said holes and inaccessibly enclosed within the locked housing.

CHARLES E. HODGKINS.
